UNITED STATES PATENT OFFICE.

CARLOS STRICKHouser, OF PHILADELPHIA, PENNSYLVANIA, ASSIGNOR TO FRIED-BERGER-AARON MANUFACTURING COMPANY, OF PHILADELPHIA, PENNSYLVANIA, A CORPORATION OF PENNSYLVANIA.

DESIGN FOR LACE TRIMMING.

51,562.

Specification for Design. Patented Dec. 11, 1917.

Application filed April 19, 1917. Serial No. 163,300. Term of patent 7 years.

To all whom it may concern:

Be it known that I, CARLOS STRICKHouser, a citizen of the United States, residing in Philadelphia, county of Philadelphia, and State of Pennsylvania, have invented a new, original, and ornamental Design for Lace Trimming, of which the following is a specification, reference being had to the accompanying drawing, which forms a part thereof.

In the manufacture of different kinds of lace trimming, such as edgings and insertions, it is customary to associate various body designs with sewing-on edges, braiding spaces and scallops or borders, etc., which may be of either of conventional or novel design. A fabric embodying my new

design is intended more particularly for use as such a body design for edgings and insertions, although it is also adapted for independent use as a trimming of any kind.

The figure is a plan view of a number of repeats of a lace trimming embodying my new design.

I claim—

The ornamental design for a lace trimming, as shown.

In testimony of which invention, I have hereunto set my hand, at Philadelphia, on this 17th day of April, A. D. 1917.

CARLOS STRICKHouser.
